Des. 328

Ezra Ripley of Troy N. Y. Assignor to
George W. Eddy of Waterford N. Y.
Letters Patent No. 328. Dated Oct 22. 1850.

The Schedule referred to in these Letters Patent and making part of the same.

To all whom it may concern:

Be it known that I, Ezra Ripley of Troy, in the County of Rensselaer, and State of New York, have invented or produced a new design of harlow stove plates, which are designated as No. 2, and I do hereby declare that the following is a full, clear, and exact description of the same, reference being had to the annexed drawings, making a part of this specification, in which fig. 1. is a view of the front, fig. 2. of the top, fig. 3. of the bottom, and fig. 4. of the end plates of the stove. Figures 5 and 6 are cross sections in the dotted lines X. X. of figures 1 and 4.

The distinguishing feature of my design is a representation of a town clock face combined with ornaments and mouldings on the front and other parts of the stove as represented in the drawings.

What I claim and desire to secure by Letters Patent, is the design, and configuration of ornamented harlow stove plates, substantially the same as described and represented.

Witnesses.
C. L. Ware
E. L. Brundage

Ezra Ripley
